UNITED STATES PATENT OFFICE.

SAMUEL MAXFIELD, OF LUTON, ENGLAND, ASSIGNOR TO JOHN CHADWICK KERSHAW, MATTHEW PLUMMER, JAMES HENRY SCHOFIELD, AND HERBERT EDMUND CAIN, ALL OF LUTON, BEDFORD, ENGLAND.

APPARATUS FOR MANUFACTURE OF HATS.

1,185,697.

Specification of Letters Patent.

Patented June 6, 1916.

Application filed August 12, 1915. Serial No. 45,118.

To all whom it may concern:

Be it known that I, SAMUEL MAXFIELD, residing at 72 Upper Princess street, Luton, in the county of Bedford, England, a subject of the King of Great Britain, have invented certain new and useful Improvements in Apparatus for the Manufacture of Hats, of which the following is a specification.

10 This invention relates to the manufacture of hats.

The object of the invention is to provide an improved apparatus whereby time and labor may be saved and cost of manufacture 15 reduced.

The invention will be described with reference to the steaming and blocking of felt hats but it could equally well be applied to the blocking of straw and other hats.

20 In the manufacture of felt hats as now and hitherto carried out, the felt hood previously proofed with shellac or gum or similar material is covered with a cloth and heated and damped by steam, the steam 25 escaping into the atmosphere and rendering it saturated with moisture. The hood is then placed in a wood mold or curler and pulled over the edge of the curler and tied with string. A crown block is then inserted and pressed down into the curler. The 30 hood is allowed to remain in the press for about 20 minutes to dry and cool. If removed too soon it shrinks and loses its shape; it is then dried in a drying room or in the 35 air which takes 3 hours to 24 hours according to which method is used and the atmospheric condition.

According to this invention the hood which has been previously proofed with 40 shellac, gum or other material is steamed in a closed receptacle. The hood is then placed within the annulus of a metal curler heated by steam; it is then pulled over the edge of the curler and tied by string, then 45 a metal or metal faced crown block which has been previously heated is placed in the hood and pressed down into the curler, firstly by hand and then by screw pressure. In a few minutes the felt is sufficiently dry 50 to be removed from the metal crown block or curler.

Referring to the drawings, Figure 1 is an elevation of one form of apparatus adapted for carrying out the invention. Fig. 2 is an

end elevation. Fig. 3 is a plan. Fig. 4 is 55 a section on line A A, Fig. 1. Fig. 5 is a section on line B B, Fig. 1. Fig. 6 is a part section showing the steam heated brim pan.

Upon the frame *a* of the machine are mounted two screw presses *b b* carried on 60 arms *c c* pivoted in pillars *d d*. Beneath the frame and disposed centrally of the presses are steam pots *e e* open to the atmosphere. Centrally of the machine is a steaming chamber *f* adapted to be closed by 65 cover *g*. Beneath the bed *a* is a steam pipe *h* coiled around the steam pots *e e*. Steam pipes *j j* lead the steam to steam pots *e e* and steam pipe *k* leads the steam to the steaming chest *f*. Cocks *m m m* are provided on the branch steam pipes. The water of condensation is led away from the steam chest *f* and steam pot *e* by the pipes 70 *n n*. Centrally of each press is disposed a brim pan which is composed of a base part 75 *o* and an upper part or curler *p*. The base part is provided with a stepped recess *q* in which is disposed a steam pipe *r*. Into the recess *q* fits the curler *p* which is provided 80 with a cavity *s*. The base part *o* is preferably round in plan; likewise the part of the curler which fits into it but the upper part of the curler *t* and *v* may be oval or of irregular shape in plan and cross section according to the shape of hat which is to be 85 molded upon it. The steam pipe *r* is perforated and connected to the steam pipe *h* by the branch *w*. The water of condensation is led away by the pipes *w* and *n*. Cover *g* is hinged at 2 and balanced by 90 weights *z z* and is adapted to be opened and closed by a push bar *4* acting through bell crank levers *5* and connecting rods *6*. A stop *7* is provided to limit the movement of the push bar *4*. The push bar is supported in guides *8 8*. Within the steaming chest *f* is disposed a wooden annular tray 9 which is perforated and adapted to support the crown block *10* to be warmed and the hood *11* to be softened. The crown 100 block *10* may be metal or metal filled or partially filled with wood *12*, means being provided for securing the wood to the metal. The crown block is fashioned to pass into the annulus of the curler and is shaped to 105 produce any desired pattern of hat.

In operation the hood *11* and crown block *10* are placed in the steaming chamber *f* and

the steam turned on. Steam is also admitted to the brim pan *o* and inlet *s*. When the hood is sufficiently damp it is placed in the annulus of the curler *p* and tied down over 5 the edge *v* and pressed as previously described. Another hood and the crown block for use in the other press are then placed in the steaming chamber *f*. By the time the operator has finished tying down and pressing 10 one hat the other is sufficiently warm and damp to be placed in the press, and while the operator is pressing and tying the second hat the first is drying sufficiently to be removed from the press and the third is 15 sufficiently warm and damped to be placed in the first press. Steam can be admitted to the steam pots *e e* to keep the hood damp and warm while it is being pressed.

In the manufacture of hats in accordance 20 with this invention the use of wooden curlers and crown blocks hitherto employed are dispensed with and the difficulty arising from dye stained curlers and crown blocks is avoided. Great delay in the cooling and 25 setting of the hood in the press and further delay in drying in a drying room or in the atmosphere is avoided.

A felt hat can by this process be shaped

and dried in a few minutes as compared with hours in the process now in use. There 30 is also a saving in the number of wooden curlers, wooden crown blocks and presses required and in the amount of steam used; consequently there is a considerable saving 35 in the cost of manufacture. Steam heated curlers and crown blocks made in accordance with this invention can also be used for blocking straw and other hats where gas heated blocks are now employed.

What I claim and desire to secure by Letters Patent is:—

1. In apparatus for molding felt or other hats, a curler provided with a cavity to which steam is admitted and means for admitting steam thereto.

2. In apparatus for molding felt or other hats a brim pan comprising a base part and a curler provided with a cavity and means for admitting steam to the cavity.

In witness whereof I have hereunto signed 50 my name in the presence of two subscribing witnesses.

SAMUEL MAXFIELD.
